Atty.

UNITED STATES PATENT OFFICE.

ATHERTON D. CONVERSE, OF WINCHENDON, MASSACHUSETTS.

CHILD'S VEHICLE.

1,269,260.

Specification of Letters Patent. Patented June 11, 1918.

Application filed January 22, 1918. Serial No. 213,199.

To all whom it may concern:

Be it known that I, ATHERTON D. CONVERSE, a citizen of the United States, and resident of Winchendon, Worcester county, 5 Massachusetts, have invented certain new and useful Improvements in Children's Vehicles, of which the following is a specification.

My invention relates to the vehicles used 10 by children and known in the trade as a "kiddie-horse," it being adapted to be propelled by the child seated thereon pushing with his feet against the floor, or ground.

Devices of this character as usually constructed have a flat body or seat with wheels at the back under said seat, a steering head or post swiveled at the front of said body and a wheel or wheels on the lower end of said head or post.

One object of the present invention is to 20 provide a knock-down form of device, whereby the front steering post with the handles, the horse's head, if such be used, and the front wheel or wheels may be detached from the body and packed in knock-down condition, the assembling by the merchant or user being rendered easy and requiring no skill beyond that of a person of ordinary intelligence.

Other objects of the invention will appear hereinafter.

The invention consists in the features and combination and arrangement of parts hereinafter described and particularly pointed out in the claims.

In the accompanying drawings;

Figure 1 is a plan view of the device of the character mentioned embodying my invention.

Fig. 2 is a side elevation.

Fig. 3 is a front view.

Fig. 4 is a detail sectional view of the upper and lower portions of the steering post or head, and the block serving as a bearing therefor, and the connecting means 45 between the said upper and lower portions serving as the swivel pin, or journal of the head.

Fig. 5 is a plan view of the bearing block 50 detached with the journal pin in section.

Fig. 6 is a plan view of the front portion of the body detached.

Fig. 7 is a bottom plan view of the bearing block and the front portion of the body.

55 In these drawings 1 is the body which is preferably made of one piece of wood. This

has a broad rear portion 1^a, an intermediate portion 1^b of less width and a front enlargement 1^c. The journals of the rear wheels 2 are carried on hangers 3, suitably connected 60 to the body 1. The steering head or post, comprises an upper portion 4, which may be in the general form of a horse's head, or other suitable form pleasing to children, a lower part 4^a, which carries at its lower end 65 the journal pin or pins for the front wheel or wheels and the connecting member 4^b, which forms the journal or swivel pin for the steering head or post, this connection finding a bearing in a block or member 5, 70 consisting of an upper wedge shaped portion 5^a and a lower portion 5^b formed with or attached thereto and having its rear end 5^c extending beyond the rear end of the upper wedge portion. The upper wedge 75 portion tapers rearwardly and is adapted to fit in a socket or opening 6 in the front portion of the body, this opening corresponding in shape to that of the upper wedge shaped portion 5^a of the bearing block, this 80 portion being of the same thickness measured vertically as the thickness of the body, so that when the wedge member is in place its upper face is flush with the upper face of the body, and therefore the extension or 85 rear end 5^c of the lower part of the bearing block fits with its upper face close against the lower face of the body. This extended end 5^c has an opening 7 adapted to receive a screw 8, so that in assembling the head or 90 steering member with the body it is only necessary to thrust the wedge block 5^a into its seat or opening 6 in the body, as far as it will go, thus making a close fit between its edges and the edges of the opening and 95 whereupon the block may be fixed in position by inserting the screw 8 in the opening 7 and screwing it into the body.

It will be observed from Fig. 5 that the lower portion 5^b of the bearing block extends laterally beyond the sides of the wedge shaped member 5^a and when the bearing block is in place these lateral ledges fit closely against the underside of the body, and afford a support therefor. Should 100 either part shrink this will make no difference in the assembling as it is only necessary to seat the wedge firmly in the socket or recess 6, and secure the block by the screw, all of which may be done by an unskilled person with little or no instruction. The journal member 4^b of the head may be

of different forms, but it is preferred to use a tube of comparatively thin metal and for securing this to the upper and lower parts of the steering head or post nails or pins 9 may 5 be used, driven through the parts including the metal tubing and these nails may go entirely through the tube or through one side and so far through the other side to dent the metal thereof into the surrounding wood.

10 In order to afford a durable and good wearing bearing for the swivel pin, instead of allowing it to find a bearing in the wood of the body, as sometimes has been done, said bearing is provided in the block. This 15 block is of greater vertical thickness than the body member and thus a long bearing is afforded for the pin to turn in and this is of advantage even though the pin turns against the wood, but the best construction is that 20 illustrated in which metal plates 10 are let into the upper and lower faces of the bearing block, the recesses in which the plates lie being of a depth equal to the thickness of the plates, so that the outer faces of the 25 plates are flush with the upper and lower faces of the bearing block. The recesses are conveniently and economically made by cutting the recesses through to the side edges of the block, and the plates fit in the recesses closely and are held therein by screws 30 11. These plates have circular openings receiving the connecting journal pin which thus finds metallic bearings at the upper and lower faces of the bearing block, which 35 being of considerably greater thickness than the body member, locates these bearings at comparatively widely separated points, thus in the highest degree acting to prevent deflection of the post or head from a vertical 40 position. Washers 12 are employed between the top and bottom of the bearing block and the adjacent portions of the head or post.

The scope of the invention is not limited 45 to the details of construction shown, the latter illustrating one embodiment of the invention.

Instead of using a screw for holding the bearing block in place this may be secured 50 by a wing-nut, as shown in Fig. 7, the stem of which passes through a notch 13 in the bearing block.

As above stated the bearing block may be 55 in two pieces. These may be nailed together as at 14.

What I claim is:

1. In combination, in a device of the character described, a body member having

a recess extending in from its edge, a bearing block filling said recess, a vertically arranged steering post journaled in said bearing block, and located with its axis within the limits of the recess and means for detachably holding the bearing block within the recess, substantially as described. 60 65

2. In combination, in a device of the character described, a body member having a recess, a bearing block removably fixed at said recess, a steering post having a reduced journal portion turning in the bearing block, 70 the upper enlarged part of said post working over the upper face of the body and the enlarged lower part of said post working over the lower face of the bearing block, substantially as described. 75

3. In combination in a device of the character described, a body member having a recess extending in from its edge, a bearing block fitted in said recess, means for fixing the bearing block in said recess, and a steering head or post mounted in said block, said recess and block being of wedge shape with the small end of the wedge formation directed inwardly, substantially as described. 80 85

4. In combination in a device of the character described, a body member having a recess extending in from its edge, a bearing block fitted in said recess, means for fixing the bearing block in said recess, and a steering head or post mounted in said block, said 90 bearing block having a portion lapping upon the face of said body member, and carrying the said fixing means. 95

5. In combination in a device of the character described, a body member having a recess extending in from its edge, a bearing block fitted to said recess, means for fixing the bearing block in said recess, and a steering head or post mounted in said block, said bearing block having a portion lapping 100 upon the underside of said body member. 105

6. In combination in a device of the character described, a body member having a recess extending in from its edge, a bearing block fitted to said recess, means for fixing the bearing block in said recess, and a steering head or post mounted in said block, said bearing block having a portion extending beyond that portion which fits the recess and lapping upon the face of the body member. 110

In testimony whereof I affix my signature.

ATHERTON D. CONVERSE.
